Primary Examiner — Sheryl Lane*Assistant Examiner* — Calvin E Vansant(74) *Attorney, Agent, or Firm* — Larry L. Huston**CLAIM**

The new design for a bottle with cap, as shown and described.

DESCRIPTION

FIG. 1 is a top, front, left side isometric view of a bottle with cap embodying the new design, shown with an unclaimed valve;

FIG. 2 is a left side elevational view thereof;

FIG. 3 is a right side front elevational view thereof;

FIG. 4 is a front elevational view thereof;

FIG. 5 is a back elevational view thereof;

FIG. 6 is a top plan view thereof; and,

FIG. 7 is a bottom plan view thereof.

The dash-dash-dash-dash (— — —) broken lines shown in the drawing views are included for the purpose of illustrating environmental structure and form no part of the claimed design.

1 Claim, 5 Drawing Sheets(56)
